UNITED STATES PATENT OFFICE.

WALTER L. HARTZELL, OF WILKINSBURG, PENNSYLVANIA, ASSIGNOR TO WESTINGHOUSE ELECTRIC & MANUFACTURING COMPANY, A CORPORATION OF PENNSYLVANIA.

METHOD OF AND APPARATUS FOR DRILLING WELLS.

Application filed May 31, 1918. Serial No. 237,586.

To all whom it may concern:

Be it known that I, WALTER L. HARTZELL, a citizen of the United States, and a resident of Wilkinsburg, in the county of Allegheny and State of Pennsylvania, have invented a new and useful Improvement in Methods of and Apparatus for Drilling Wells, of which the following is a specification.

10 My invention relates to a method of and apparatus for electrically drilling oil wells, and particularly to an electrical means of cable drilling in which a drilling tool or bit is fastened to a cable suspended from a walking beam that is rocked or operated by electric motive power.

The power requirements of the different drilling operations vary through a wide range. The power required for operating the drilling tool is more or less continuous, while that required for handling the casing of the well and for bailing is very intermittent.

The tool on the end of the cable is alternately lifted and dropped by the walking beam, and to obtain efficiency in the drilling operation, when the tool is dropped, the "power" or "drive" must automatically speed up so that when the tool 25 strikes the drilling blow and rebounds the cable will catch the tool and lift it on the up-stroke before it starts to fall back again. This cycle is continued as the drilling progresses but, in order to be able to drill 30 rapidly and prevent excessive wear and breaking of the drilling cable, with each depth of well and with different weights of tools and with different formations to be drilled through, the speed of the motor 35 must be variable to give the best working speed, and the speed must increase rapidly when the tool is dropped and this "pick up" speed must be adjustable with increasing depths so that the cable will be ready 40 to pick the tool up on the rebound after it has struck the drilling blow. Furthermore, the driving power must be of sufficient capacity to handle the casing for the well and other necessary operations.

45 Heretofore, a single comparatively large slip-ring, variable-speed, alternating-current electric motor of from 50 to 75 horse-

power capacity has been used for all purposes. Smaller motors have been used but generally have proven too small to handle 55 the casing satisfactorily. While only from 15 to 30 horsepower is needed for the actual drilling, the extra capacity is required to handle the steel casing which is from 60 12 to 24 inches in diameter and so heavy 65 that a string of it weighs tons. Since the actual drilling involves about 90% of the total operations, there is a considerable waste of power when such a large motor is used and, inasmuch as the motor carries 70 only about one-fourth load, it gives a poor power factor and low efficiency, which makes the cost of power high. The control of the speed of the large drilling motor is effected by the use of a 9-point main 75 controller and an auxiliary controller connected in series with the main controller, whereby a rough and a fine speed adjustment may be obtained during the drilling operation. Since there is but a small load 80 on the motor, the range of the possible speeds is very limited, and the "pick up" of the motor to synchronous speed will be slow on account of the large inertia of 85 its rotor. These limitations and defects of 90 the single large electric drilling motor render it impossible to obtain and maintain the proper "motion" of the bit and the same therefore often operates "dead," that is, it does not always strike the proper 95 drilling blow as it rebounds dead. Furthermore, a single large motor is very uneconomical because of the increased cost of power due to the low power factor and low efficiency, and the slow rate of drilling 100 makes the interest, labor cost and overhead expenses high. Delay in reaching the "pay sand" allows the adjacent lease holder to obtain so much more oil, if he has operating wells, which, of course, is an indirect loss to the drilling producer. When the well is finished, the large motor, not being suitable for pumping, involves a loss in dead capital tied up in the motor and its controlling devices.

The object of my invention is therefore to provide a method and apparatus for electrically drilling oil wells that will practically eliminate the above mentioned undesir-

able features encountered in the use of a single large electric motor. To this end, I employ two or more substantially similar electric motors having their shafts mechanically connected together, and controlled by individual controllers, as hereinafter more fully explained.

The above and other objects and the novel features of my invention will be apparent 10 from the following description taken in connection with the drawing in which Figure 1 is a side elevational view of an oil well drilling apparatus embodying my invention; Fig. 2 is a plan view of the same; Figs. 3, 15 4 and 5 are views illustrating other ways of mechanically connecting the two electric motors; Fig. 6 is a group of speed-torque curves of two small electric motors mechanically connected together, showing the same 20 as used and controlled according to the method and apparatus embodying my invention; Fig. 7 is a group of speed-torque curves of a single large electric motor, as heretofore employed for drilling purposes; 25 and Fig. 8 is a group of speed-torque curves of the double-rated mechanically connected smaller motors, each developing 15 horsepower at 600 R. P. M. and 30 horsepower at 1200 R. P. M.

30 Referring to Figures 1 and 2 of the drawing, two or more substantially similar alternating current wound-rotor electric motors 10 and 11 have their rotor shafts mechanically connected together by some suitable 35 means as a common shaft coupling, belt or chain. The pulley 12, carried by a shaft mechanically connecting the two motors and driven thereby, is connected to the pulley 13 on the countershaft 14 by a belt 15, the 40 countershaft being belted to the band wheel 16 that drives the shaft 17 carrying a crank 18 connected to one end of the walking beam 19 that is pivoted at 20. The arrangement in Figures 1 and 2, whereby the motors 45 10 and 11 may be mechanically connected so that both motors can apply their power to the same load, may be varied. Figures 3, 4 and 5 illustrate three other ways of accomplishing the same purpose and still other 50 ways may be adopted. In Figure 3, the motors 10 and 11 are belted to the same band wheel 131 on the shaft 14. In Fig. 4, the motors 10 and 11 are belted by separate belts to similar band wheels 132 and 133 both 55 fast on the countershaft 14. In Fig. 5, the two motors 10 and 11 are connected by a single belt to the band wheel 134, the belt passing around an idler pulley I. The outer end of the walking beam has a drilling tool 60 or bit 21 suspended therefrom by the cable 22 that unwinds from the cable drum 23 as the bit descends and the depth of the well increases. In order to raise the tool and cable, the drum 23 may be driven from the 65 band wheel 17 by a rope 24. The motors are

preferably wound so as to normally rotate in opposite directions, so that, when the pulley ends of the armature shafts are mechanically connected together, the two armatures will rotate in the same direction.

The motors 10 and 11 are preferably each of smaller capacity than the large electric motor heretofore employed, being approximately 15 and 30 horsepower, 600-1200 R. P. M. double-rated two speed type or 15 and 75 45 horsepower star-delta, 900 R. P. M. single speed type. Each motor is equipped with a double-throw switch S for changing the connections of the windings, so as to give a low 80 rating and a high rating, or to change the number of poles and change the synchronous speed of the motors. For example, the full load power developed by the two speed type motors may be 15 H. P. at 600 R. P. M., 30 H. P. at 600 R. P. M., 30 H. P. at 1200 85 R. P. M. or 60 H. P. at 1200 R. P. M., or by the 15 and 45 horsepower "star-delta" single speed, 15 horsepower at 900 R. P. M., 30 horsepower at 900 R. P. M., 45 horsepower at 900 R. P. M., 90 horsepower at 900 R. 90 P. M. Since the motors may be operated at any one of these full load ratings, a higher efficiency and a higher power factor are obtainable, which reduces the power expense and the line loss and voltage fluctuations in 95 the transmission system.

The controlling mechanism for the mechanically connected motors 10 and 11 consists of two reversing controllers, 101, 111, one for each motor, adapted to give 100 per cent speed control in nine steps, more or less. These controllers vary the resistances 102, 112, in the secondary circuits of the motors independently of each other and, as the motors are connected together mechanically, a variation of the resistance of either motor (1) will cause the load to be shifted from one motor to the other, (2) will change the average speed, and (3) will also change the relative speed when the 110 load is on and when it is off. By varying the combination of resistances, the operator can regulate the number of strokes per minute, simultaneously with the proper ratio of the up stroke to the down stroke 115 and thereby obtain the most efficient drilling motion. The very wide range of speeds obtainable by the use of two motors and two independent controllers permits the operator to closely approximate the correct drilling motion as the depth of the well increases. This prevents the tool from drilling "dead" and renders possible a more rapid drilling, lessening the time required to reach the "pay sand", reducing the labor 120 cost and the interest charges on non-producing investments, and enabling the operator to obtain much oil that he would otherwise not get on account of slow drilling.

The feeder circuits that connect the motors 10 and 11 to the three-phase line *a*, *b*, *c*, include the line switches or circuit breakers 25 and 26, respectively, to protect the motors and to disconnect the apparatus from the power line at will. Ammeters 27 and 28 or other suitable electrical measuring meters are connected to series transformers 271 and 281, respectively, and are located in the derrick D within sight of the operator to indicate to him what proportion of the load each motor is taking. Levers 29 and 30, connected by cables 291 and 301 to the drums of the controllers 101 and 111, respectively, are also located at the operator's position in the derrick. A maximum torque relay (not shown) may also be connected to the high rated side of each motor and arranged to insert resistance in the secondary circuit thereof so each motor will give a maximum torque at zero speed.

Since the motors 10 and 11 are each nearer the capacity required for drilling operations, they may be operated at approximately full load instead of less than one-quarter load, as in the case of the single larger motor, and, therefore, the maximum range of speed control may be obtained on each motor during the drilling operation. From the curves of Fig. 7, it will be seen that a 75 horsepower drilling motor operating under a load of about 15 to 20 horsepower and controlled by a main controller and auxiliary controller connected in series gives a limited range of operating speeds and a very limited range of "pick-up" speeds. For example, the "pick-up" speed for point "1", indicated by that part of curve *m* between "1" and *X* or synchronous speed, is but slightly greater comparatively than the "pick-up" speed for point "9" of the controller, which is indicated by that part of curve *n* between "9" and *X*. The "pick-up" speeds for the intermediate points of the controller are between points "1" and "9" and, of course, the range of "pick-up" speeds is thus quite limited. With the use of the auxiliary controller, operating speeds may be obtained between those corresponding to the steps of the main controller but the range is necessarily limited by the main controller.

Assuming that power is applied to one motor only, the other motor running idle, and the torque required to lift the tool is equal to the 15 horsepower or the full load torque of one motor, then 9 different speeds can be obtained corresponding to the 9 points of the controller for the main motor, as indicated by the points I, II, III, IV, V, VI, VII, VIII, IX on the curves at the right of line *OX* in Fig. 6. In each case, when the tool is dropped, the speed will accelerate to the point *X*.

Again, assuming the same torque condi-

tion but with power applied to both motors and the controllers for each motor operated on the same relative controller point, then each motor will take one-half of the total load or develop a torque corresponding to $7\frac{1}{2}$ horsepower and a further 9 different speeds will be obtained, as indicated on Fig. 6 by the points *a*, *b*, *c*, *d*, *e*, *f*, *g*, *h* and *9*. In each case, when the tool is dropped, the speed will accelerate to the point *X* but with a different acceleration period than with the power only driving the one main motor. Although some of the speeds obtained are approximately the same, the rate of acceleration to the point *X* is different.

By using different points on the auxiliary controller from those on the main controller, a large number of different speeds can be obtained, as indicated by the points on the curves between the $7\frac{1}{2}$ horsepower and 15 horsepower lines, and in each case with a different acceleration rate to the point *X* when the tool is dropped.

The particular combination I have shown and described gives a total of 54 points with a considerable range of both speed and acceleration rate, using the same size motors and 9-point controllers and similar resistances. These results can all be modified by (1) using different size motors, (2) using controllers having more or less controller points, (3) using more controller points on one controller than on the other and (4) using resistances of different capacities.

However, for simplicity and commercial reasons, it is more desirable to use motors and controllers of the same size. The resistance connections can easily be varied if any particular results are desired or, if necessary to get lower control steps, more resistance can be added to the auxiliary motor with very little trouble and expense.

The inherent accelerating capacity of the two small motors is greater than that of the single large motor, since their diameters are approximately one-half that of the larger motor and their combined weight is about the same, the fly wheel effect or inertia which varies as WR^2 is about one-fourth that of the large motor. For this reason, the acceleration of the main and auxiliary motor will be much quicker than the single large motor when the tool is dropped, which, in conjunction with the greater speed range and the adjustment of the pick-up speed make this apparatus and method especially suitable for drilling at varying depths, with different weights of tools and through different formations.

Referring to Fig. 6, since the torque required to lift the tool is constant and equal to *OM* or the torque at 15 horsepower, both the speed and the proportion of the load carried by either motor can be obtained from the curves for any setting of the main

and auxiliary controllers by simply finding the points where the distance between the curves corresponding to the main controller and the curve corresponding to the auxiliary controller is equal to OM. This is shown on the drawing by lines A—B—C, for two combinations. AB represents the load on the main motor and BC the load on the auxiliary motor. In each case $AB+BC=OM$, or the total torque required to lift the drilling tool.

The pull-out torque or maximum torque of each motor is represented by OL and OL', or a total torque equal to L'L can be exerted by the two motors.

15 The curves of Figure 8 represent the double rating obtained when throwing the switches on the 15/30-600/1200 R. P. M. motor. The curve FXF' is the same as shown in Fig. 6. The curve GX'G' is the 20 curve on the ninth point, or with resistance all out and the motors operating on the high rating side. The curve HX'H' shows the operation when the amount of resistance is cut into the secondary on the high side to 25 give maximum torque at zero speed which is automatically obtained on the high rating side of the motor when a maximum torque relay is used. The maximum torque or pulling power of the two motors is HH'. When 30 using the 15/45 horsepower star-delta connected motor, similar curves are obtained except the speed is not changed.

With either the double-rated two-speed motor or the double-rated star-delta connected motor, the maximum torque or pull-out torque on the high rating side is from 35 three to four times full load torque so that with the two motors a torque equal or greater than that of the large single motor 40 is obtained and also the same speed control is obtained on the high rating side as on the low rating side, giving great flexibility and quick operation. Also, in operations like bailing sand which require less 45 power than handling casings, one motor can be used instead of two and thus again adapt the motor capacity to the work at hand giving better efficiency and power factor and reducing power consumption.

50 The equipment used for drilling can be used without any change or additional expense for pumping two separate wells.

From the foregoing, it will be seen that, 55 by the use of a driving means consisting of two independently controlled but mechanically connected electric motors, I am able to do all of the work heretofore accomplished by the use of a single large motor, and, in addition, numerous advantages are 60 obtainable that are not possible with the single large motor. A greater range of speeds and rates of acceleration are obtainable, and greater rapidity and economy in operation are possible. While I have shown 65 and described the method and apparatus in

detail, it will be understood that numerous modifications may be made therein without departing from the spirit and scope of the invention.

What I claim is:

1. The method of drilling wells that comprises operating the drilling tool by means of a plurality of mechanically connected electric motors, and controlling the division of load on said motors independently to vary the total driving capacity of said plurality of mechanically connected motors over a relatively wide range.

70 2. The method of drilling wells that comprises operating the drilling tool by a plurality of mechanically connected electric motors, and controlling the load carried by said motors independently to permit of a relatively wide range of speed at small increments.

80 3. The method of drilling wells that comprises operating the drilling tool by power derived from two electric motors having mechanically connected rotors, and electrically controlling said motors independently to permit of a wide range of speeds and loads.

85 4. The method of drilling wells that comprises operating the drilling tool by power derived from two alternating current electric motors having mechanically connected rotors, and electrically controlling each motor independently of the other, whereby a large range of resultant driving speeds are obtained for operating the drilling tool.

90 5. The method of drilling wells that comprises operating the drilling tool by power derived from two electric motors having the rotors thereof mechanically connected together, and controlling each motor independently of the other, whereby the total driving capacity of the combination of the mechanically connected rotors may be varied.

100 6. The method of drilling wells that comprises operating the drilling tool by power derived from two alternating current electric motors having rotors mechanically connected to the same driven member, and resistances in circuit with the windings of 110 said rotors, and varying the resistance in one rotor circuit independently of the resistance in the other rotor circuit to permit of a wide range in speed at small increments.

115 7. The method of drilling wells that comprises operating the drilling tool by means of a plurality of mechanically connected motors and controlling said motors independently to vary the division of power between them whereby the driving speed thereof is varied over a relatively wider range than is obtained by a single motor.

120 8. The method of drilling wells that comprises operating the drilling tool by means 125

of a plurality of mechanically connected electric motors and controlling said motors independently to vary the division of power between them whereby the driving speed thereof is varied over a relatively wider range than is obtainable by a single electric motor of the capacity of said plurality of motors.

9. The combination with well drilling apparatus having a vertically reciprocating tool or bit, of operating means for reciprocating said tool comprising a plurality of mechanically connected induction motors, and means for controlling such motors independently of one another to obtain a wide range of resultant speeds in a comparatively great number of steps whereby the rate of acceleration or "pick-up" speed of such operating means synchronizes with such drilling tool during substantially its entire operation and under the various drilling conditions encountered.

10. The combination with a well drilling apparatus, of means for operating the same comprising two mechanically connected double-rated electric motors, and controllers for independently varying the output and speed of said motors whereby the motors develop low torque low speed for drilling and high torque high speed for other operations.

11. The combination with power transmitting means, of a plurality of alternating current electric motors arranged for severally and jointly supplying power to said means, and means for independently controlling said electric motors to vary the speed and division of power developed thereby.

12. In a power plant for drilling wells, the combination with a walking beam, a drilling tool operatively connected to one end and a band wheel operatively connected to the other end, of two electric motors for driving the band wheel, and means for so dividing the load between the motors as to obtain a wide range of speed in the band wheel.

13. In a power plant for drilling wells, the combination with a walking beam, a drilling tool operatively connected to one end and a band wheel operatively connected to the other end, of two alternating current electric motors having wound secondaries for driving the band wheel, and means for independently varying the resistance of said

secondaries whereby unbalanced load conditions are obtained.

14. The combination with two mechanically connected wound-secondary induction motors, of means for independently controlling the speed torque characteristics of said motors during the joint operation thereof by means of varying the secondary currents thereof.

15. In a well drilling device, the combination with a drilling tool and two induction motors for actuating the drilling tool, of independent controllers for so controlling the ratio of the speeds of the motors on the down stroke and the up stroke as to synchronize with the time period of the drilling tool.

16. In a well drilling device, the combination with two induction motors for actuating the drilling tool, of means for so controlling the ratio of the speeds of the motors on the down or loaded stroke and the up stroke as to synchronize with the time period of the drilling tool.

17. In a well drilling device, the combination with a drilling tool and a casing, of two operatively connected motors, and means for so independently controlling the motors that they may be changed from low torque low speed operating means for the tool to high speed high torque handling means for the casing.

18. Well drilling apparatus comprising a drilling tool and means for operating the same comprising two mechanically connected induction motors having wound-secondaries and means for independently varying the resistances of said secondaries to change the speed-torque characteristics of said operating means.

19. In an oil-well drilling system, the combination with a drilling tool and electric driving means therefor, of means for periodically accelerating the driving means at the top of the drill stroke.

20. In an oil-well drilling system, the combination with a drilling tool and electric driving means therefor, of means for periodically accelerating the driving means at the top of the drill stroke and for periodically slowing down the driving means at the bottom of the drill stroke.

In testimony whereof, I have hereunto subscribed my name this 23rd day of May, 1918.

WALTER L. HARTZELL.
